GRILLEWORK FOR TREILLAGES, ROOM DIVIDERS OR THE LIKE

Arthur A. Schlott, Jr., Louisville, Ky., assignor to Julius Blum & Co., Inc., Carlstadt, N.J., a corporation of New York

Filed Feb. 4, 1964, Ser. No. 78,516

Term of patent 14 years

(Cl. D54—2)

FIG. 1 is an elevational view of a grillework for treillages, room dividers or the like, showing my new design, it being understood that the grillework has this pattern throughout;

FIG. 2 is an enlarged longitudinal, sectional view taken along line 2—2 of FIG. 1;

FIG. 3 is an enlarged longitudinal sectional view taken along line 3—3 of FIG. 1;

FIG. 4 is an enlarged longitudinal sectional view taken along line 4—4 of FIG. 1;

FIG. 5 is an enlarged transverse sectional view taken along line 5—5 of FIG. 1, and

FIG. 6 is an enlarged transverse sectional view taken along line 6—6 of FIG. 1.

I claim:

The ornamental design for a grillework for treillages, room dividers or the like, substantially as shown and described.
